(57) **CLAIM**

The ornamental design for a cap for medical breathing apparatuses, as shown.

DESCRIPTION

FIG. 1 is a top perspective view of the cap for medical breathing apparatuses showing my new design;

FIG. 2 is a front section view taken along section line 2-2 of the FIG. 1 device;

FIG. 3 is a bottom plan view of the FIG. 1 device;

FIG. 4 is a top plan view of the FIG. 1 device; and,

FIG. 5 is a front elevation view of the FIG. 1 device, the left side, right side, and rear elevation views being identical thereto.

1 Claim, 1 Drawing Sheet
